WELL PACKER

Ferdinand J. Spang, Butler, Pa.

Application February 10, 1940, Serial No. 318,287

10 Claims.

(Cl. 166—12)

This invention relates to well packers, and its principal object is to produce a packer that may be automatically set by an upward stress of the tubing on which it is run, whereby the tubing is kept in more perfect vertical alignment than with the conventional well packer operated by compressive force.

Another object is to produce a packer for use with a string of tubing and which, by means of said tubing, may be easily set in position within a well and easily adjusted to unset or released position, when it is desired to remove the same from the well.

A further object is to produce a packer having means for automatically retracting the slips and subsequently locking them in their retracted position, whereby they may be made inoperative.

A still further object is to provide, in connection with a well packer having its anchoring means located above the packing element, a debris cup for the purpose of collecting miscellaneous debris that may enter the well bore above the packer.

The packer of this invention is constructed for use with a string of tubing and broadly comprises a novel combination of the following elements:

An expandible tubular packing element; a wall gripper, including a series of slips and a conical expander for expanding or moving the slips into gripping position; a carrier for the slips and which is provided with a series of "wiper springs" which tend to hold the slip carrier against longitudinal as well as rotational movement; means for positively moving the slips to unset or contracted position when it is desired to remove the packer from the well, and a debris collecting cup located above the slip carrier.

In the drawings:

Figure 1 is a view mainly in elevation of a packer embodying this invention and in condition to be lowered into position within a casing or a bore hole;

Fig. 2 is a view in elevation of the packer and shows the same as it appears after the slips have been set or forced into contact with the wall of a casing or bore hole, but before the rubber packing element has been expanded into contact with such walls;

Fig. 3 is a view similar to Fig. 2 but shows the rubber packing element expanded into contact with the wall of a casing or bore hole as the case may be;

Fig. 4 is a longitudinal section of the packer and shows the position of the parts as they appear

when the packer is adjusted for removal from the well;

Fig. 5 is an enlarged fragmentary sectional view illustrating certain parts of the packer;

Fig. 6 is a transverse section of the slips and expander and is taken on line VI—VI of Fig. 4; and

Fig. 7 is a transverse section taken on line VII—VII of Fig. 4.

10 The expandible tubular packing element, to which reference has been made, is numbered 10, is preferably formed of live rubber, and more or less loosely surrounds a relatively short section of tubing 11. This packing element is located 15 between an end member 12 which is threaded onto the lower end of tubing section 11 and a conical slip expander 13 which also loosely surrounds tubing section 11. Packing element 10 preferably has metal band-like members 14—14 20 molded into its opposite ends as disclosed in Fig. 3 of United States Patent 820,149, and these band-like members are secured to end member 12 and slip expander 13 by means of screws 15.

Tubing section 11 is threaded at its upper end 25 to receive a coupling member 16. This coupling member is provided with an inwardly extending flange 17 at its upper end, and between this flange and the upper end of tubing section 11, an outwardly extending flange 18 of a tubing section 19 is located.

Suitable packing material 20 is confined between this flange and the upper end of tubing section 11 and prevents leakage through the rotative joint thus formed between tubing sections 25 11 and 19. Coupling member 16 serves as an upper stop for the slip expander.

The conical portion of slip expander 13 is provided with a series (preferably four) of undercut grooves 21 within which slips 22, formed to fit said grooves, are slidably mounted. The slips are thus dovetailed to the expander and are free to slide lengthwise thereof. The slips are slid into place through the lower ends of the undercut grooves, and their upward movement within the grooves is limited by stops 23 located at the upper ends of said grooves. In other words, grooves 21 terminate short of the upper end of the expander element 13.

50 A sleeve 24, preferably formed of bronze, and of less length than tubing section 19 surrounds said tubing section and is provided with a longitudinally extending internal groove to accommodate a spline 25 which is welded to and projects radially outward from tubing section 19; sleeve 24 being thus splined to tubing section 19 is

caused to rotate with said section while free to slide lengthwise thereof.

Sleeve 24, throughout the major part of its length, is provided with external square right-hand threads 28.

The slip carrier above referred to is numbered 27 and preferably takes the form of a steel tube which surrounds bronze sleeve 24. This steel tube, adjacent its lower end, is provided with square internal threads 29 which mesh with threads 28. Threads 29 are preferably cast in place, from Babbitt or some other suitable metal alloy; the tube being drilled with a number of holes so that during the casting procedure, the cast metal flows into said holes, as shown at 28, 10 15 and anchors the cast metal in place.

A series (preferably four), of friction springs 30, termed "wiper springs" in the industry, are secured at their upper ends by rivets 31 to the slip carrier. These springs which are outwardly bowed and have their lower ends free to slide in contact with the outer surface of the carrier, are of such size and stiffness as to be capable of firmly gripping the inner wall of the casing or of the bore hole as the case may be, and frictionally hold the slip carrier and therefore the slips, in adjusted position while the packer is being lowered into position in a well. In this adjusted position, the slips are in contact with stops 23.

Slip carrier 27 is connected to slips 22 by means of links 32; the upper ends of the slips being bifurcated to receive the links which are secured in place by means of pins 33. A member 34 threaded onto the lower end of the slip carrier is provided with a series of pairs of spaced ears 35; and the upper ends of said links are secured in place between said ears by means of pins 36.

A coupling member 37, utilized to connect upper tubing section 19 to the lowest section 38, of the string of tubing, has a "neoprene" cup 39 secured thereto. This cup serves to prevent sediment which falls from the wall of the bore hole or falls into the casing from reaching the slip assembly and other parts of the packer. Coupling 37 also serves as a stop for limiting upward movement of bronze sleeve 24; sleeve 24 may be said to float between coupling members 16 and 37.

A tubing section 40 is threaded into a tapped opening in member 12 in line with tubing section 11 and is perforated or otherwise constructed to admit oil, when the packer is used in a well having considerable oil and comparatively light gas pressure; under these conditions the packer is used to build up sufficient pressure to cause the well to flow its production. If the packer is not thus used to build up pressure, a shoe or anchor may be threadedly secured to member 12.

In Figs. 1 to 4 inclusive, 41 represents either the inner wall of a casing or the wall of a bore hole.

The slip carrier, the floating bronze sleeve, the slip grooves in the expander and the rotative joint carrying packing 26 are preferably filled or coated with a graphitic type of lubricating and rust-preventing grease in order to insure free working of the packer even after the same has remained in a well for a considerable period of time.

In order to adjust the packer or make it ready for lowering into a casing or bore hole, the parts are adjusted to the positions shown in Figure 1. In other words, the bronze tubular member 24 is moved up into contact with cou-

pling 31. The slip carrier is screwed to its bottom position. This is accomplished by holding slip carrier 27 against rotation while rotating tubing section 19. With tubular member 24 in contact with its top limit stop 31, and the slip carrier screwed to the bottom of tubular member 24, slips 22 are retracted, or in other words, are in their innermost position at the upper limit of their travel and in contact with stops 23. At this time, packer element 16 is collapsed.

Setting the packer within a casing or bore hole is easily accomplished by merely lowering it to the proper position and then pulling up on the tubing string. Pulling up on the tubing string raises tubing sections 19 and 41; the wiper springs which tend to hold the slip carrier against downward movement, while the packer is being lowered to position, keep the slips in contact with stops 23. Likewise the wiper springs tend to hold the slip carrier against upward movement when the tubing string is being pulled up.

Pulling up the tubing string first expands the slips against the wall of the casing or bore hole as the case may be, and then foreshortens packing element 16, expanding the same into packing contact with such wall. The string of tubing is then secured in raised position within the casing head in the ordinary manner.

When it becomes necessary or desirable to remove the packer from the well, the following procedure is carried out:

The tubing is first lowered until the lower end of coupling member 16 (which cooperates to form the packed rotative joint) contacts with the top of cone expander 18. When this occurs, packing element 16 is collapsed to its normal or smallest diameter and slips 22 are likewise contracted to their smallest diameter; with the slip carrier 27 in its lowermost position. The string of tubing is then rotated in a clockwise direction, and, since the bronze sleeve is splined to tube section 19, it also rotates in a clockwise direction. This rotation of sleeve 24 causes it to screw downward through the slip carrier 27 until it contacts with the top of coupling member 16; the slip carrier being held against rotation by the wiper springs. The final unset position, with the slips in fully retracted position, is illustrated in Fig. 4.

It is within the scope of this invention to position the packing element 16 at some distance from the slip expander 18 and fill the space therebetween with any practical separating or spacing means, in order that the slips may be set within and at the lower end of the casing and the packing element 16 be located at some distance below the casing, in order that it may pack the formation for the purpose of separating strata of oil and gas or of either oil or gas. In this manner the slips may be set in a location where they will be firmly held in place yet easily removed; whereas, packing element 16 may be set in an irregularly formed hole which while practical for packing, would not be practical as a seat for the slips.

Having thus described my invention, what I claim as new and desire to secure by Letters Patent is:

1. In a packer for oil and gas wells, an expandible packing element mounted on a tubular body, a slip assembly mounted above said packing element comprising a slip expander, a cylindrical slip anchor threadedly engaged to the inner of a pair of sleeves for limited vertical movement,

means on said cylindrical slip anchor to prevent rotation and means on the inner of said sleeves to cause rotation whereby the relative vertical relationship of said sleeves may be changed from an active position to any inactive position.

2. A slip assembly for anchoring a well tubing comprising a slip expander, multiple slips, a slip actuator comprising an outer internally threaded tubular member and an inner externally threaded tubular member co-actively engaged therewith for limited relative vertical movement, means for restraining movement of the outer tubular member during rotation of the inner tubular member whereby their relative vertical positions may be altered to change said slip actuator from a position of activity to a position of non-activity.

3. In combination with a slip assembly as claimed in claim 2, a sediment cup for collecting debris falling from above said slip assembly.

4. In a slip assembly for well tubing, multiple slips mounted on an expander and connected to the outer of a pair of telescopic sleeves threadedly engaged together and mounted on said tubing for limited vertical movement, means for rotating the inner sleeve, and wiper springs carried by the outer sleeve for restraining the rotation thereof whereby said sleeves are relatively repositioned from an active to an inactive position.

5. In an anchoring assembly for well tubing, multiple slips mounted on an expander and connected to an internally threaded sleeve restrained against rotative movement in the well bore; said internally threaded sleeve being threadedly engaged with a second sleeve mounted on the well tubing for limited vertical movement and positive rotative movement therewith whereby rotation of the tubing moves the two sleeves from a position of vertical activity to a position of non-vertical activity.

6. In a packer for oil and gas wells, an expandable packing element, a slip assembly above said packing element and which includes slips and a slip expander; a pair of telescopically arranged tubular members above the assembly and provided with interengaging means for changing their relative longitudinal position by relative rotation thereof, means for holding the outer of said tubular members against rotation and means for rotating the inner tubular member.

7. In a packer for oil and gas wells, an expandable packing element, a slip assembly mounted above said packing element and including slips and a slip expander; a pair of telescopically arranged tubular members having interengaging threads, means connecting the outer tubular member to said slips, means for rotating the in-

ner of said members and means for resisting the rotation of the outer of said members.

8. In a packer for oil and gas wells, an expandable packing element mounted on a tubular body, a slip assembly above said packing element and including slips and a slip expander; a tube section aligned with said tubular body, means constructed and arranged to hold said body and tube sections together against lengthwise separation but to permit relative rotation thereof, a pair of telescopically arranged tubular members surrounding said tube section and provided with interengaging threads for changing their relative longitudinal position by relative rotation thereof, means for holding the outer of said tubular members against rotation and means for rotating the inner tubular member.

9. In a gas and oil well packer of the type having an expandable packing element mounted on a tubular body and a slip assembly above said element and in which the slips of said assembly are moved to operative position and the packing element expanded by an upward thrust exerted on said tubular body; the combination with said slip assembly of means for positively moving its slips from operative to inoperative position, and which includes outer and inner threadedly engaged tubular members, means connecting the outer member to said slips, a section of tubing within and splined to said inner member, means connecting said section of tubing to said tubular body and which is of such construction as to cause said body and tube section to move together vertically but which permits relative rotation therebetween, and means for restraining movement of the outer tubular member during rotation of the inner tubular member by said section of tubing whereby the relative vertical positions of said tubular members may be altered.

10. In a gas and oil well packer of the type having an expandable packing element mounted on a tubular body and a slip assembly above said element, and in which the slips of said assembly are moved to operative position and the packing element expanded by an upward thrust exerted on said tubular body; the combination with said slip assembly of means for positively moving its slips from operative to inoperative position and which includes outer and inner threadedly engaged tubular members, means connecting the outer of said members to said slips, means for rotating the inner of said members and means for restraining movement of said outer member during rotation of the inner member whereby the relative vertical position of said members may be altered.

FERDINAND J. SPANG.
